UNITED STATES PATENT OFFICE.

WILLIAM I. THOMPSON, OF STONEHAM, MASSACHUSETTS, ASSIGNOR OF ONE-THIRD TO
ANTHONY M. LUX AND ONE-THIRD TO WALTER J. LUX, BOTH OF WOBURN, MASSA-
CHUSETTS.

TARGET PLACING AND SHIFTING APPARATUS.

Specification of Letters Patent.

Patented Oct. 19, 1915.

1,157,342.

Application filed July 24, 1914. Serial No. 852,968.

To all whom it may concern:

Be it known that I, WILLIAM I. THOMPSON, a citizen of the United States, and resident of Stoneham, in the county of Middlesex and State of Massachusetts, have invented certain new and useful Improvements in Target Placing and Shifting Apparatus, of which the following is a specification.

This invention relates to targets used for practice with rifles and other fire arms held by the marksman, and particularly to targets used in armories, shooting galleries, rifle ranges, and the like, in shooting competitions, a considerable number of targets being used during each competition.

The object of the invention is to provide an apparatus enabling the members of a series or pack of targets, stored at a target station or bulkhead, to be automatically and accurately placed successively in position to be fired upon, and automatically removed from said position and retrieved, or carried to the firing station for inspection, the apparatus being controlled entirely from the firing station, so that there is no occasion for the presence of any person at the target station during the competition, danger of accidental shooting of any of the competitors being therefore eliminated, and the time required to place and remove each target being reduced to the minimum.

The invention consists in the improvements which I will now proceed to describe and claim.

Of the accompanying drawings forming a part of this specification,—Figure 1 represents a side view of an apparatus embodying my invention. Fig. 2 represents a section on line 2—2 of Fig. 1, and a side view of that part of the apparatus seen at the left of said line. Fig. 3 represents a section on line 3—3 of Fig. 1, and a side view of that part of the apparatus shown at the right of said line. Fig. 3^a represents a side view of one of the target-lifting grippers. Fig. 3^b represents a section on line 3^b—3^b of Fig. 3^a, and an end view of said gripper. Fig. 3^c represents a view similar to Fig. 3^b, showing the gripper opened. Fig. 4 represents a section on line 4—4 of Fig. 3. Fig. 5 represents a section on line 5—5 of Fig. 3. Fig. 6 represents a side elevation of a portion of the apparatus. Fig. 7 represents a top view of a part of the structure shown by Fig. 6. Fig. 8 represents an enlargement of

a portion of Fig. 6, parts being shown in section. Fig. 9 represents a section on line 9—9 of Fig. 1, and an elevation of parts at the left of said line. Figs. 10 and 11 are elevations of opposite sides of a portion of the apparatus. Fig. 10^a represents a top view of the portion shown by Fig. 11. Fig. 12 represents a top view of the carrier. Fig. 13 represents a side view of the carrier. Fig. 14 represents a side view of a portion of the carrier. Fig. 15 represents a section on line 15—15 of Fig. 12. Fig. 16 represents a bottom view of the carrier. Fig. 17 represents a section on line 17—17 of Fig. 6. Fig. 18 represents a section on line 18—18 of Fig. 4. Fig. 19 represents an enlargement of a portion of Fig. 3. Fig. 20 represents a section on line 20—20 of Fig. 19. Fig. 21 is a sectional view of the chute which receives the retrieved targets. Fig. 22 is a view similar to Fig. 21 showing only the lower end of the chute with the target shown in a different position.

The same letters of reference indicate the same parts in all of the figures.

The opposite end portions of a rifle range are shown by Fig. 1, in which *a* indicates the firing station, and *b* the target station where a target 12 (Fig. 3) is held in position for use. At the target station is a target magazine 13 (Figs. 3 and 4) containing a pack of loose paper targets 12, means being provided for feeding the targets one at a time downwardly from the magazine between target-lifting grippers (Figs. 3^a, 3^b and 3^c), each composed of an inner jaw 14 attached to a sprocket chain 15, and a swinging outer jaw 14^a. The chains 15 run in fixed vertical guides 16, (Fig. 3), there being two chains and two pairs of guides, and are driven by sprocket-wheels 17, the shafts 18 of which are connected by bevel gears 19, 19^a, with a transverse motor driven main driving shaft 20. 21 represents a reversible induction motor of standard type, adapted to be rotated in different directions by reversing the polarity of the current which rotates the armature of the motor. The motor shaft 22 is connected by sprocket-wheels and a sprocket chain 23 with a shaft 24 which is connected by a small gear 25 and a large gear 26 (Fig. 4) with the main driving shaft 20.

When the apparatus is ready for use, the lifting grippers are depressed and closed on

a target 12, which is in position for use. When a shot has been fired from the station *a* the motor 21 is started by closing the current through it by a circuit closer, such as 5 a three point switch 27 (Fig. 1) at the station *a*, the polarity of the current being such as to cause the lifting-grippers to rise and lift the target to the carrier gripper hereinafter described, which carries the used 10 target to the firing station. As the lifting-grippers approach the upper end of their movement, the swinging jaws 14^a encounter vertical gripper-opening fingers 28 (Figs. 10 and 11) which open the lifting-grippers 15 to release the raised target by swinging the jaws 14^a outwardly, as shown by Fig. 3^c. The fingers 28 are attached to arms 29 pivoted at 30 to swing horizontally. The swinging gripper jaws are provided with 20 sockets 14^b (Fig. 3^b) which receive the fingers 28 when the grippers approach the upper extreme of their movement. The fingers 28 are swung outwardly by levers 31 (Figs. 10 and 11) pivoted at 32 to fixed supports 25 and projecting into the paths of the lifting-grippers. When the jaws 14 of the lifting-grippers encounter the levers 31, said levers are swung upwardly and act through connecting rods 33, rocking levers 34, rods 35, bell-crank levers 36, links 37, and swinging levers 38, to swing the shifting fingers 28 outwardly, thus swinging the jaws 14^a outwardly and opening the lifting-grippers. The swinging gripper jaws 14^a 30 are held open during their subsequent downward movement by ears 39 on said jaws engaging the guides 16, as shown by Fig. 3^c, where one of the guides is shown by dotted lines.

40 The guides 16 are provided at their lower portions with openings 135 (Figs. 3 and 19) and at their upper portions with openings 135^a (Fig. 10); the lower openings 135 being arranged to permit the jaw ears 39 to 45 swing outwardly out of the guides 16 when the target grippers reach the lower extreme of their movement, while the upper openings 135^a are arranged to permit said ears to swing inwardly into the guides 16 when 50 the grippers reach the upper extreme of their movement. Springs 136 (Figs. 3^a and 19), connected with the gripper jaws, act to swing said ears outwardly out of the guides 16 when they reach the lower openings 135. 55 The shifting fingers 28 act to swing said ears inwardly when they reach the upper openings 135^a, as above stated. Movable stops or guides 5 (Figs. 9 and 10) are located in the upper openings 135^a and are 60 supported by rods 6 movable in fixed guides 7, 8. Springs 9 on said rods, bearing on the guide 8 and on shoulders on the rods 6, yieldingly hold the guides 5 in the projected position shown by Figs. 9 and 10. When 65 the ears 39 are swung inwardly by the shift-

ing fingers they strike the movable guides 5 and displace or retract the same. After the ears have passed inwardly through the openings 135^a the guides 5 spring forward behind the ears and prevent them from being forced by the springs 136 outwardly out of the guides 16.

One of the levers 31 is connected by a rod 40 (Fig. 9) with one end of a walking-beam 41 pivoted at 42 to a fixed support. The opposite end of said walking-beam engages and actuates a plunger 43 which opens the carrier gripper hereinafter described, and also engages and actuates a lever 44 pivoted at 45 to a fixed support. To said lever is pivoted a strut 46 which engages and moves the plunger 47, operating a three point switch which acts in conjunction with the polarity switch, hereinafter described, to close the circuit through two trolley rails 47^a supported by a T-shaped track 48 (Fig. 17) extending from the target station to the firing station, said trolley rails being thus energized and transmitting current to a standard reversible induction motor 49 attached to a wheeled carrier 50 which runs on tracks 51, (Fig. 17) extending between the stations *a* and *b*.

The function of the carrier is to carry a target-transferring gripper between the stations *a* and *b*, said gripper being composed of jaws 52, 52 pivoted at 53 to the frame of the carrier. The carrier is provided with traction wheels 54, 55 running on the tracks 51, the wheels 55 being idle, and the wheels 54 connected with the motor 49 by suitable train of gearing, such as that shown by Fig. 15, said train including gears 56 attached to the shafts of the wheels 54, and a worm 57 on the motor shaft 58. The carrier is provided with pivoted trolley arms or brushes 59, (Figs. 12 and 17) which are held in yielding contact with the trolley rails 47^a and are in circuit with the motor 49, so that when the circuit is closed, as 100 stated, the motor is energized.

The transferring gripper jaws are normally held open, as shown by dotted lines (Fig. 15), by a leaf spring 60, attached at one end to a block 61 secured to the carrier 115 frame, and a notched rod 62 slidable in guides on said frame, said rod having two notches 63, 64 (Fig. 15) which alternately receive the free end of the spring. Each transferring gripper jaw has a rod 65 (Fig. 120 15) attached to the arm portions of said jaws. To the rods 65 are attached arms 66, 67. The arm 67 is pivoted at 68 to the notched rod 62. The arm 66 is connected with the arm 67 by a link 69, and has a slot 70 which permits it to oscillate and move endwise on a fixed rod 71.

When the carrier is at rest at the target station *b*, the gripper jaws 52 being open, the jaws are closed by mechanism provided 125

for that purpose, including the plunger 43, a cross-bar 72 in the path of said plunger and supported by the longer arms of bell-crank levers 73 (Fig. 13) pivoted at 74 to the carrier frame, links 75 pivoted to the shorter arms of said levers, levers 76 pivoted at 77 to the carrier frame, and links 78 connecting the levers 76 with the gripper jaws 52.

10 When the plunger 43 is depressed, it depresses the cross-bar 72 which acts through the connections last described to close the gripper jaws 52 on the upper edge of a target 12 previously interposed between said jaws while they were opened. The closing movement of the jaw to which the arm 66 is pivoted, causes said arm to impart an end-wise movement to the notched rod 62 in the direction of the arrow, (Fig. 15). Said rod 20 has a rack 80 (Fig. 15) meshing with a pinion 81 on a shaft 82 journaled in the carrier frame, and carrying a polarity switch 83 which is thus moved to position to close the circuit through the trolley rails 47^a and 25 cause the carrier to travel toward the firing station. The notched rod 62 forms a part of mechanism for opening the jaws 52 and releasing the target when the carrier reaches the firing station. Said mechanism includes 30 a lever 85 (Fig. 16) pivoted at 86 to the carrier frame and projecting obliquely therefrom to come in contact with a fixed shoe 87, shown by dotted lines (Figs. 1 and 16) near the firing station, the lever being provided 35 with a trundle roll 88, adapted to run in frictionless contact with the shoe, which is provided with an oblique face 87^a adapted to force the outer end of the lever 85 inwardly when the carrier approaches the firing station. The lever acts through a rod 40 89 (Fig. 16) pivoted at 90 to its inner end, a rocking lever 91 pivoted at 92 to the carrier frame, and pivoted at one end to the rod 89, a rod 93 pivoted to the other end of the 45 rocking lever, a rocking lever 94 pivoted at 95 to the carrier frame, and pivoted at one end to the rod 93, and a stud 96 on the notched bar against which one arm of the lever 94 bears loosely when the gripper jaws 50 are closed.

It will now be seen that when the oblique lever 85 strikes the fixed shoe 87, it is swung inwardly and opens the gripper jaws 52 through the described mechanism. The 55 movement of the notched rod 62 caused by the jaw-opening operation, moves the polarity switch 83 through the rack 80 and pinion 81, so that the polarity of the current is reversed and the carrier motor 49 is caused 60 to rotate in the direction required to return the carrier to the target station where it is arrested with the jaws 52 open.

To insure the stoppage of the carrier with its jaws exactly located in the path of the 65 target raised by the lifting-grippers, I pro-

vide a spring buffer which is compressed or set for action by the carrier when it is approaching the end of its return movement and yieldingly or gradually stops the carrier and then mechanically moves the carrier outwardly or forward a short distance, determined by a fixed stop, the location of which determines the location of the carrier jaws 52, means being provided for breaking the circuit through the carrier motor and 75 stopping the operation thereof before the motion of the carrier is reversed by the spring buffer.

The carrier is provided with an arm 97 (Fig. 6) having a striking end face 98 and a 80 downwardly opening notch 99. 100 represents a slide movable in fixed guides and having a striking end face 101 (Fig. 8) opposed to the face 98, and a block or projection 102 to which is attached a plunger 103. 85 Said plunger plays in a fixed cylinder or dash-pot 104^a, in which is a buffer spring 105 (Fig. 6) bearing on the plunger 103. To the outer end of the slide 100 is pivoted 90 at 104 a detent lever 106 having a hook 95 adapted to enter the notch 97. A fixed track 107 having an incline 108 is adapted to support the detent lever 106 in a raised position, as shown by full lines (Figs. 6 and 8). The spring 105 acts on the plunger 103 to 95 normally hold the slide 100 projected against a fixed stop member 109 which is so located that it co-operates with the buffer spring 105 in holding the carrier jaws in their exact 100 predetermined position.

110 represents a circuit-breaking switch, the plunger 111 of which is engaged with a strut 112 pivoted to one arm of a lever 113. Said lever is pivoted at 114 to a fixed support, and its other arm has a trundle roll 105 115 projecting into the path of the block or projection 102 on the slide 100. When the carrier approaches the end of its return movement from the firing station, the detent lever 106 is depressed, as shown by dotted 110 lines (Figs. 6 and 8). The striking face of the carrier arm 97 abuts against the striking face of the slide 100 and moves the slide backwardly, thus causing the detent lever to ride up the incline 108, the hook of the detent lever 106 being thus caused to engage 115 the notch 99 in the arm 97, as shown by Fig. 6. The detent lever is held in this position by the track 107. The backward movement of the slide causes the projection 120 102 to act through the lever 113, strut 112, and switch plunger 111 to break the circuit through the carrier motor, so that the carrier is now moved only by its own momentum, which is gradually checked by the 125 buffer spring 105. The spring 105 now reacts and moves the slide and carrier outwardly until the movement is arrested by the stop 109. The detent lever 106 is held 130 in its raised position by a spring 119 at-

tached at 120 to the slide 100, and having at its free end a pin 121, which yieldingly engages a socket in the detent 106 to hold the latter in its raised position until the plunger 5 43 is again depressed by the ascent of the target-lifting grippers. The plunger passes through an orifice in a cross-bar connecting the detent levers (of which there are two located at opposite sides of the track 48), 10 and is provided with a collar 123 (Fig. 8) which bears on and depresses the detent levers just after the plunger acts on the jaw-closing cross-bar 72.

The target-lifting grippers, after opening 15 and releasing the raised target, are returned to their starting position while opened, and are closed on another used target 12, as next described.

One of the sprocket-chains which carry 20 the lifting-grippers is provided with a tap-pet 125 which is arranged to move a polarity switch 126 (Fig. 3) located in suitable proximity to the exposed target and to the target-lifting motor 21. One arm of the 25 switch 126 projects into the path of the tap-pet 125, which acts to move the switch and change the polarity of the current through the motor 21, and thus reverse the direction of its rotation just after the raised lifting- 30 grippers open to release the raised target, the lifting-grippers being therefore moved downwardly to their starting position, and the swinging jaws of the grippers being held open by the guides 16, as shown by Fig. 3^c.

When the grippers nearly reach the end of 35 their downward movement, they actuate the plunger 128 (Figs. 2 and 3) of a three-point switch, to break the circuit and stop the motor. A lever 130 (Fig. 3) pivoted at 40 to one of the guides 16, has its free end projecting into the path of one of the lifting-grippers, and is arranged to be depressed thereby just before the grippers reach the lower end of their movement. The lever 45 acts through a link or strut 133 on the switch plunger 128, and moves the switch to break the circuit. At the same time, the ears 39 on the swinging gripper jaws are brought into coincidence with the lower 50 openings 135 (Fig. 3) in the guides 16, said openings being formed to permit the ears 39 to pass through them. The swinging jaws are now closed by the springs 136 connected with the fixed and swinging jaws. Said 55 springs are compressed by the opening of the swinging jaws and act to close said jaws when the ears 39 coincide with the openings 135. The polarity switch 126 is connected with the strut 133 of the circuit-breaking 60 switch by jointed links 142, 143, so arranged that when the lever 130 is moved to break the circuit through the motor 21, the polarity switch 126 is moved to position to change the polarity of the current when the 65 circuit is again closed, so that the next op-

eration of the motor 21 caused by operating the three-point switch 27 at the firing station will raise the target-lifting grippers. The lifting grippers are now held stationary at their lowest position and opened preparatory to grasping a target. 70

The target magazine 13 is provided with means for feeding targets one at a time, the feed being so timed that the target being fed is controlled by the feeding means while the used target is being raised, and before another target can be fed from the magazine, so that there is no liability of exposing more than one target at a time in position to be fired upon. 75

The feeding mechanism comprises a fluted upper feed roll 146 (Figs. 3 and 4) journaled in bearings at opposite ends of the magazine and occupying a slot in the front side of the magazine, the inner side of the 80 roll bearing on the target 12 at the outer side of the pack. 85

Below the upper feed roll 146, is a pair of lower feed rolls 147, between which the target passes. The rolls 147 are connected by gears 148 (Fig. 5) so that they rotate in opposite directions. The shaft of one of the lower rolls 147 has a gear 149 meshing with an intermediate gear 150 which meshes with a gear 151 on the shaft of the upper feed roll 146. The three feed rolls are driven from the shaft 20 through a vertical shaft 153 (Fig. 3) connected by bevel gears 154, 155, with a transverse shaft 156, having a gear 157^a meshing with the gear 100 26 on shaft 20, and by bevel gears 157, 158, with the shaft of one of the lower feed rolls 147. The feed rolls therefore, are all driven by the motor 21, and they are so timed that while the lifting grippers are raising a used target, a fresh target is fed downward and is released from the nip of the rolls 147, just before the upward movement of the lifting-grippers is arrested. The target drops behind vertical ears or guides 160 upon a horizontal shelf 161 and is supported by said shelf in such position that when the lifting-grippers again descend, the inner jaws pass behind it and the outer jaws in closing, bear on its outer side and press it against the 110 inner jaws, which are preferably provided with spurs 163 (Fig. 3^c) on which the target is impaled. 115

At the firing station *a* is a vertical chute 164 (Fig. 21) having a flaring mouth, which 120 is arranged to receive the target released by the opening of the carrier jaws 52. Said chute communicates with a magazine 165 for the used targets, having a hinged glazed door 166 at its front side through which the 125 targets may be inspected, said door permitting the removal of the targets. At the edges of the chute are sheet metal guides having portions 167, 168 which are differently inclined and are so arranged that the 130

lower end of a target entering the magazine 165 will be first deflected toward the back of the magazine, as indicated by dotted lines in Fig. 21. Said bottom has inclines 169, 170, the incline 169 being arranged to cause the lower end of a target deposited upon it to move toward the front of the magazine, and its upper end to swing backwardly from the path of the next target falling through the chute, as indicated by Fig. 22. As the targets accumulate in the magazine 165 they gradually move backwardly and upwardly on the incline 169, and then backwardly and downwardly on the incline 170 until they reach the back portion of the magazine. Provision is therefore made for keeping the last target at the front of the pack of targets dropped into the magazine.

I prefer to provide the unused target magazine 13 with a follower adapted to press the pack of targets forward. Said follower which is shown by Figs. 4 and 18, comprises a gang of elongated loose horizontal rolls, 175, journaled in end bars 176 which are connected by a cross-bar 177. The follower has a swinging connection with the back of the magazine through links pivoted to said back and cross bar. The follower therefore tends to constantly press the pack toward the front of the magazine, the rolls 175 being in rolling contact with the rear target of the pack, so that there is no frictional resistance to the forward and downward movement of the targets on the bottom of the magazine, which is inclined as shown by Fig. 4. I also prefer to provide brake shoes 180, one of which is shown by Fig. 15, said shoes being applied to the carrier wheels 54 to gradually check the momentum of the carrier when it is approaching each end of its course. The brake shoes are normally held out of contact with the wheels, and are forced into contact therewith by fixed blocks 181, 182, (Figs. 1 and 8) located near opposite ends of the track 48, and having oppositely inclined bottom faces. These inclined faces are in the paths of levers 183, one of which is shown by Fig. 15, pivoted at 184 to the carrier frame and normally held by springs 185 in the raised position shown by dotted lines, said levers having trundle rolls 186 adapted to run on the said inclined faces.

The levers 183 are connected with the brake shoes 180 by suitable means, such as the links 187, bell-crank levers 188, and arms 189, shown by Fig. 15, the levers 188 being pivoted at 190. When the lever roll 186 encounters either of the blocks 181 or 182, the levers 183 are depressed, as shown by dotted lines, and act through the described connections to press the brake shoes against the wheels.

To the notched rod or slide 62 is connected a spring 62^a, which tends to pull said rod in

the direction of the arrow, (Figs. 15 and 16), and yields to allow the rod to be moved in the opposite direction by the lever 85, and the intermediate connections. The spring 60 is a relay or detent spring, and cooperates with the notches 63, 64, in holding the rod and the polarity switch 83 in either of two positions. The lever 85 is yieldingly projected or pressed outwardly from the carrier by a spring 85^a (Fig. 16).

The track 48 may be supported in any suitable way, preferably by a beam 192 (Fig. 1) coextensive with the track and connected therewith by bolts or hangers 192. The beam may be supported from the top of a building or apartment in which the apparatus is located.

Operation: A target being exposed at the station *b*, and the motors 21 and 49, being inoperative, a shot is fired from the firing station *a*. The switch 27 at that station is then operated to close the circuit through the motor 21, the polarity switch 126 being now in position to cause rotation of said motor in the direction required to lift the target. The motor now operates to raise the target-lifting jaws. At the same time the feed rolls on the target magazine 13 are rotated to feed down a fresh target, which drops when released by the feed rolls, loosely, in the path of the target-lifting jaws, where it remains until the said jaws descend to grasp it. The lifting jaws insert the upper end of the used target between the now open carrier jaws 52. Before the lifting jaws reach the end of their upward movement, they strike the lever 31, which successively actuates the devices which open the lifting jaws, and the devices which close the carrier jaws, and the switch which closes the circuit through the carrier motor 49. The opening of the lifting jaws and the closing of the carrier jaws are nearly simultaneous. When the carrier jaws close, the polarity switch on the carrier is shifted to drive the carrier motor in the direction required to move the carrier to the firing station. The switch which admits the current to the trolley rails 47, is operated by the upward movement of the elevating jaws after the carrier jaws are closed on the target, and the carrier is then propelled to the firing station. When the carrier reaches the firing station, the obliquely projecting lever 85 pivoted to the carrier, strikes the fixed shoe or deflector 87 at the firing station, which displaces the lever inwardly, the lever acting through the intermediate mechanism to open the carrier jaws. The used target drops into the chute 164, which conducts it to the magazine 165. The opening of the carrier jaws shifts the polarity switch on the carrier and reverses the rotation of the carrier motor 49, so that the carrier immediately returns to its starting point, where

it remains with the jaws open ready to receive the next used target. Just as the elevating jaws open, the tappet 125 on one of the lifting-jaw carrying chains 15, acts on 5 the polarity switch 126 and reverses the rotation of the motor 21, so that the lifting jaws which are now open, descend to their lowest position. Just as the lifting jaws reach their lowest position, one of said jaws 10 strikes the switch lever 130 which acts to move the three-point switch controlling the elevator motor 21 and stop the motor, and at the same time to move the polarity switch 126, so that when the circuit is again closed 15 at the firing station, the motor will rotate in the direction required to raise the lifting jaws. When the ears 39 on the swinging lifting jaws reach the openings 135 in the guides 16, the jaws are free to be closed 20 by their spring on the unused target. It will now be seen that the apparatus, after being started from the firing station, acts automatically through a cycle of movements or operations, commencing with the 25 lifting of a used target from the point at which it was exposed, and terminating automatically with the return of the retrieving carrier to the target station, after the retrieved target has been delivered at the firing station, a fresh target being placed in 30 position at the target station during the said cycle. While the reversible motors 21 and 49, may be started, reversed, and stopped by mechanical means, I prefer for 35 obvious reasons to employ electrical means, comprising the standard three-point and polarity switches above referred to. I have not shown said motors and switches in detail, nor the electrical connections or wiring, these being matters well understood by 40 practical electricians.

The mechanism and parts surrounding the placed target at the target station should, of course, be suitably protected against injury from stray bullets, by a suitable guarding structure which I have not represented. 45

The track and the means coöperating therewith for retrieving used targets may be omitted, and the used targets stored, or left 50 at or near the target station, at a point near the target-exposing holder, in case it is not desirable to retrieve the targets at the firing station, in which case a used-target magazine similar to that above described, 55 may be located at the target station in position to receive used targets shifted from their exposed position.

It will be seen that each target is positively controlled during its course from the 60 unused target magazine to the firing station, and is moved by gravity only after its release from the grippers on the carrier at the firing station, each target being positively moved from the unused target magazine to 65 its exposed position at the target station,

and positively moved from said position to the carrier grippers. The apparatus is therefore adapted to control targets of thin flexible paper.

I claim:—

1. An apparatus of the character stated, comprising a firing station, a target station, a track between said stations, and mechanism controlled from the firing station for transferring a used target from the target 75 station to the firing station, and placing a fresh target in an exposed position at the target station, said mechanism including a carrier movable on said track and having target grippers, means for positively moving targets successively from the target station to said grippers, and means for opening the grippers and releasing the targets at the firing station. 80

2. An apparatus of the character stated, 85 comprising a firing station, a target station, a track between said stations, and mechanism controlled from the firing station for placing targets at the target station, transferring a used target from the target station to the firing station, releasing the used target at the firing station, and placing a fresh target in an exposed position at the target station, said mechanism including a carrier movable on said track and having 90 target grippers, means for positively moving unused targets successively to the target station, means for positively moving used targets successively from the target station to said grippers, and means for opening the grippers and releasing the targets at the 95 firing station. 100

3. An apparatus of the character stated, comprising a firing station, a target station, a track between said stations, and mechanism controlled from the firing station for transferring a used target from the target station to the firing station and placing a fresh target in an exposed position at the target station, said mechanism including 110 target-lifting grippers at the target station, means for closing said grippers on a placed target, means for alternately raising and lowering said grippers, means for opening the raised grippers to release the target, and means for engaging the raised target and moving it along said track to the firing station. 115

4. An apparatus of the character stated, comprising a firing station, a target station, a track between said stations, and mechanism controlled from the firing station for transferring a used target from the target station to the firing station and placing a fresh 120 target in an exposed position at the target station, said mechanism including means for raising a used target from its exposed position, means for releasing the raised target, a carrier movable on said track and having a gripper, means for closing the carrier 125 130

gripper on the raised target, and means for propelling the carrier on said track.

5. An apparatus of the character stated, comprising a firing station, a target station, a track between said stations, and mechanism controlled from the firing station for transferring a used target from the target station to the firing station and placing a fresh target in an exposed position at the target station, said mechanism including target-lifting grippers at the target station, a reversible electric motor and means co-operating therewith adapted to raise and lower said grippers, means being provided for closing the grippers on an exposed target when they are lowered, and for opening the grippers when they are raised, a carrier movable on said track, having a gripper adapted to engage a raised target, a reversible electric motor on said carrier, adapted to propel the carrier in either direction on the track, means being provided for closing the carrier gripper on a raised target when the carrier is at the inner end of the track, and for opening said gripper when the carrier is at the outer end of the track, means for starting the carrier motor after the closing of the carrier gripper, means for reversing the carrier motor after the opening of said gripper, and means for stopping the motor when the carrier is returned to the inner end of the track.

6. An apparatus of the character stated, comprising a firing station, a target station, a track between said stations, a support for maintaining a target in an exposed position at the firing station, and operating mechanism including means for placing a target on said support, grippers for raising a target from the support after use, a reversible motor for raising and lowering said grippers, means being provided for starting, reversing and stopping said motor, a carrier movable on said track from station to station, means on the carrier for engaging the raised target when the carrier is at the inner end of the track, means for releasing the raised target when the carrier is at the opposite end of the track, a reversible motor on the carrier for propelling the latter, means being provided for starting, reversing, and stopping the carrier motor, and

means controlled from the firing station for starting a cycle of movements of said operating mechanism, said movements being automatically stopped at the end of the cycle.

7. In an apparatus of the character stated, a used target receiver comprising a chute with a flaring mouth, a target magazine communicating with the lower end of the chute and extending backwardly therefrom, and edge guides in the magazine adapted to deflect a descending target and locate its upper edge behind the path of a following target.

8. A target-controlling apparatus comprising a firing station, a target station, and operating mechanism controlled from the firing station and having provisions for positively moving targets successively to an exposed position at the target station, positively moving the targets successively from said position, and releasing the removed targets.

9. A target-controlling apparatus comprising a firing station, a target station, having a target magazine and a target-exposing holder, and operating mechanism controlled from the firing station and having provisions for positively moving targets successively from the magazine to the holder, positively moving the targets successively from the holder, and releasing the removed targets.

10. A target-controlling apparatus comprising a firing station, a target station, having an unused-target magazine and a target-exposing holder, a used-target magazine, and operating mechanism controlled from the firing station and having provisions for positively moving targets successively from the unused-target magazine to the holder, positively moving the used targets successively from the holder to a position over the used-target magazine, and releasing and removing targets when in said position.

In testimony whereof I have affixed my signature, in presence of two witnesses.

WILLIAM I. THOMPSON.
